VARIABLE PRESSURE FLUID DRIVE MECHANISM

Joseph Zubaty, Flint, Mich., assignor to General Motors Corporation, Detroit, Mich., a corporation of Delaware

Application September 16, 1957, Serial No. 684,193

3 Claims. (Cl. 123—140)

The invention relates to a fluid drive mechanism and more particularly to a mechanism of the wobble plate type as used in fluid pumps. The drive and the controls therefor may be used with a pump of the type disclosed in my application Serial No. 633,456, entitled "Variable Pressure Fluid Pump," and filed January 10, 1957.

The fluid drive includes an oscillating member which imparts reciprocal motion to pump plungers which operate to pump fluid at a desired pressure and volume. It is often desirable to vary the delivery characteristics of such pumps in accordance with the load impressed on associated mechanisms such as internal combustion engines. A pump embodying the invention has the pump actuating ring interconnected with a diaphragm responsive to engine vacuum so that movement of the diaphragm in response to the changes in the engine vacuum automatically adjust the stroke of the pump, thereby adjusting the delivery characteristics of the pump. A pump embodying the invention is sensitive to load on the engine since centrifugal force acting on the actuating ring and the vacuum caused by the action of a venturi tube at the engine air intake tend to balance each other. During rotation, the oscillating member will tend to occupy a position normal to the axis of rotation due to centrifugal force. The degree of this tendency is proportional to the square of the speed of the drive shaft. The angle of tilt of the oscillating member is controlled by vacuum imposed by a venturi tube used on the engine intake. The depression tendency of the vacuum sensitive diaphragm is proportional to the square of the air mass flow. These two tendencies will be balanced and pump output depending on load without interference of speed will result.

In the drawing:

The figure illustrates a pump embodying the invention and having parts in section.

The pump illustrated includes a housing 10 with which a web 12 is integrally formed. A bearing hub 14 is located centrally within web 12. Bearing 16 is received within hub 14 and provides a rotatable mount end and locating point for the end of drive shaft 18. A second bearing 20 is mounted on the other end of drive shaft 18 and is located in the bearing cap and seal 22. Cap 22 is secured to a pump cover 24. Several stacked plates which may be separated by gaskets are positioned intermediate pump cover 24 and housing 10. These plates include a plunger guide plate 26, a pressure chamber plate 28, and a valve plate 30. Pump cover 24 may be provided with an inwardly extending sleeve 32 on which plates 26, 28, and 30 are piloted. The valve, passage, and chamber arrangement may be similar to that shown in the above identified application. The pressure chambers 27 may contain the piston springs 29 and be connected with the inlet 21 through inlet annulus 33 and inlet valves 35. Outlet valves 37 connect the chambers 27 with outlet annulus 39 and the outlet 41.

The pump diaphragm 34 is positioned intermediate plates 26 and 28 and is used both as a pump diaphragm and a gasket. Plunger guide plate 26 has plunger cylin-

2

ders 36 formed therein in which pump plunger pistons 38 are reciprocably received. These pistons engage diaphragm 34 at their outer ends and, when reciprocated, cause the diaphragm to flex, thereby imparting pumping action to the diaphragm. Plunger pistons 38 may be integrally formed with plunger arms 40 which terminate at their ends opposite the pistons in rounded ends 42. Sockets 44 are formed within actuating ring 46 and the ends 42 of the plunger arms 40 are received in the sockets.

10 Actuating ring 46 is preferably mounted on the outer race of bearing 48. The inner race of this bearing is secured to hub 50 of oscillating member 52. Hub 50 extends circumferentially about drive shaft 18 and is radially spaced from that shaft. Actuating ring 46 may be tilted relative to the axis of drive shaft 18 by pivotal movement of oscillating member 52. Oscillating member 52 is rotatably driven from drive shaft 18 through drive pin 54 and driving member 56. Oscillating member 52 is pivotally attached to driving member 56 by hinge 58. The axis of hinge 58 provides the pivot point for oscillating member 52 and actuating ring 46. Actuating ring 46 may be prevented from rotating with respect to housing 10 by pin 64 which extends downwardly from web 12 and engages ring 46 in recess 66.

15 25 An initial manual adjustment of the oscillating member 52 may be obtained by threading tapered adjusting screw 62 inwardly or outwardly in the correspondingly threaded dependent lug attached to the lower side of oscillating member 52. The tapered end of screw 62 may contact bevel surface 60 which is formed on one side of driving member 56 adjacent screw 62. When the screw 62 is moved inwardly, the minimum tilt angle obtainable between oscillating member 52 and driving member 56 is increased.

30 35 The pump is preferably controlled during engine operation by vacuum sensed at a venturi throat in the engine air intake system. A typical system of this type is shown in application Serial No. 591,889, filed June 18, 1956, in the name of John Dolza and assigned to the common assignee. A vacuum sensitive diaphragm 70 is provided for this purpose. Cover plate 72 may be suitably secured to pump housing 10 so that web 12 and the cover plate form a space divided by diaphragm 70 to define atmospheric chamber 74 and vacuum chamber 76. What is claimed is:

1. In a fluid pump of the wobble plate type, a housing, a drive shaft rotatably mounted in said housing, internal combustion engine means driving said shaft, an oscillatable member secured to said shaft for rotation therewith, means permitting angular movement of said oscillatable member relative to the axis of said shaft, a wobble plate actuating member secured for oscillatory movement with said oscillatable member relative to the axis of said shaft, and differential pressure means for adjusting the angular relationship of said member relative to said shaft, said differential pressure means being sensitive to the second power of the air mass flow of said engine means, said oscillatable member when rotating having a centrifugal force component sensitive to the second power of the speed of said drive shaft and opposing said differential pressure means whereby said members are angularly adjusted relative to said drive shaft in direct proportion to the load on said engine means.

2. A vacuum controlled variable pressure pump having a tilttable actuating ring and reciprocable pistons driven by said ring, a drive for said ring, a chamber formed in one end of said pump for having a diaphragm extending therethrough, one side of said diaphragm being sensitive to vacuum proportional to the second power of a load characteristic of said ring drive, connecting means interconnecting said diaphragm and said ring, said ring drive exerting a component of centrifugal force on said ring acting opposite to the force of said vacuum on said diaphragm transmitted through said connecting means to said ring whereby said ring is tilted in direct proportion to the load on said drive.

3. A wobble plate fluid pump having a drive shaft, an

internal combustion engine operatively connected to said shaft in driving relation therewith, a driving member secured about said drive shaft for rotation therewith, an oscillating member pivotally attached to said driving member at a point spaced from the axis of said shaft, a pump actuating ring secured on said oscillating member for oscillatory movement therewith, a plurality of pump pistons disposed concentrically about said drive shaft and actuated by oscillatory movement of said actuating ring, and means for tilting said actuating ring and said oscillating member relative to said driving member on said drive shaft, said tilting means including a diaphragm sensitive to a differential pressure, said differential pressure being directly proportional to the second power of the air mass passing through the intake of said engine, said oscillating member exerting a component of centrifugal force proportional to the second power of the speed of said drive shaft on said actuating ring in opposition to the force of said differential pressure exerted on said diaphragm.
